UNITED STATES PATENT OFFICE

HARRY W. PROTZELLER, OF EAST CHICAGO, INDIANA, ASSIGNOR TO O. F. JORDAN COMPANY, OF EAST CHICAGO, INDIANA, A CORPORATION OF INDIANA

RAILROAD SPREADER

Original application filed July 26, 1928, Serial No. 295,451. Divided and this application filed December 9, 1929. Serial No. 412,645.

This invention relates to improvements in railroad spreaders and it consists of the matters hereinafter described and more particularly pointed out in the appended claims.

5 The present application, is a divisional application and the subject matter thereof, was first presented in my copending application for patent on railroad spreaders filed July 26, 1928 under Serial Number 295,451, now Patent No. 1,822,312.

10 The primary object of the invention is to provide in a railroad spreader, an improved brace construction between the car and main spreader wing and one which may be locked at any point in its extended position to prevent any telescoping of the parts under the great loads imposed upon the wing.

15 Another object of the invention is to provide a brace construction devoid of any locking pin and hole arrangement so that the parts may have a relative turning during the changing of the vertical angular position of the wing and may be readily locked together irrespective of the vertical angular position 20 of the wing.

25 Still another object of the invention is to provide a telescopic brace for the wing, the parts of which brace may be frictionally locked together and this by a novel arrangement of parts carried by the brace itself.

30 These objects of the invention as well as others, together with many advantages thereof will more fully appear as I proceed with my specification.

35 In the drawings:—

Fig. 1 is a top plan view of a railroad spreader embodying the improved form of wing brace.

40 Fig. 2 is a detail view in side elevation on an enlarged scale of the associated end parts of the brace and the means for locking said parts together.

45 Fig. 3 is a transverse vertical detail sectional view on a further enlarged scale as taken on the line 3—3 of Fig. 2.

Fig. 4 is a detail view in side elevation of one of the levers embodied in the locking means for the brace.

50 Fig. 5 is another detail sectional view as taken on the line 5—5 of Fig. 3.

Fig. 6 is a horizontal detail sectional view as taken on the line 6—6 of Fig. 5.

Referring now in detail to that embodiment of the invention illustrated in the accompanying drawings, 1 indicates as a whole 55 the car of a railroad spreader and 2—2 indicates the main spreader or side wings, arranged one at each side of the car. In Fig. 1 the decking of the car has been omitted for the purpose of more fully showing the under 60 framing thereof.

Said under framing includes side sills 3—3 suitably connected together and extending from end to end of the car. At the front end of the car and spaced laterally outward from 65 said sills are shorter sills 4—4 thus providing a wider frame or platform part 5 at said end of the car which is pointed in the usual manner to accommodate the associated V-shaped front plow 5a.

At the rear end of the car and spaced laterally from the sills 3—3 are shorter sills 6—6 which are suitably connected together and the front end of each shorter sill 6 is offset inwardly to meet and be secured to an 70 associated sill 3. This provides a wider frame or platform part 7 at the rear end of the car and associated with each platform is a suitable wheel truck 8—8. The construction just above generally described, provides 75 a substantially arrow shaped car body with wider front and rear end parts and a narrower intermediate part, thus forming cut in or recessed sides for the car in which the wings are disposed when the car is in transit 80 from one point of use to another.

At each side of the car, a suitable distance to the rear of the wider front platform part 5 is an upright wing carriage post 9, suitably secured to and supported from the side sills. 90 Each post is preferably tubular and mounted thereon for vertical guided movement in a hinge bracket plate 10. Said bracket is preferably bifurcated to receive the inner end of a wing 2 and said wing is hinged in the bracket plate by a horizontal pin 11. Suitably connected to each post is an arm 12 the free end of which is connected to a piston 13 of a compressed fluid cylinder 14 carried on the car under framing as best shown in 95 100

Fig. 1. As is apparent in said figure each cylinder is disposed on that side of the car opposite the one upon which its associated wing is located. Thus when fluid under pressure is admitted to one end of a cylinder it will swing the associated wing about its carriage post, away from the car as best shown at the bottom of Fig. 1, and when fluid under pressure is admitted to the other end of said cylinder, the wing is swung in toward the side of the car as best shown at the top of said Fig. 1. As the construction just described will form the subject matter of a separate application to be filed later, it will not be described in detail herein.

With each wing is associated a power cylinder 15 by which the wing may be swung into different vertical angular positions about the pin 11 which connects the inner end of the wing to the bracket plate 10. From the above, it is apparent that the wing may be readily swung from an inoperative position parallel with the cut in sides of the car to an operative position at an angle thereto and that when said wing is in its operative position, its outer end may be swung up or down to give the desired vertical angularity thereto.

Associated with each wing is one or more braces, the function of which is to hold the wing in the desired angular position with respect to the car and to receive the thrust or load imposed upon the wing in service and to transmit it to the under framing of the car. Heretofore the braces have been made of telescopic I-beam and channel arrangement and in some cases telescopic tubes are employed but in each instance locking pins and holes were provided to lock the braces in the desired extended position. Such arrangements have not proven satisfactory because the position of the locking pin in the desired hole, determined the angular position of the wing and in some instances the correct angle could not be attained because of the location of the pin and hole. Again with the I-beam and channel brace, a serious twist was imposed upon the same when changing the vertical angle of the wing and when telescopic tubular members were employed having locking pins and holes, the pin could not always be brought into position with the hole because of the radial angular displacement between the two due to the relative twisting between the tubular brace parts when the vertical angular position of the wing was thus changed.

The present braces, now about to be described, eliminate the objections above noted. As shown in Fig. 1, I provide inner and outer braces 16 and 17 for each wing and as they are substantially alike in structure and only different in length, a detailed description of one will suffice for both.

Each brace includes inner and outer tubu-

lar members or pipes 18 and 19 respectively. In this instance the inner pipe member 18 is of a larger diameter, and on the outer end thereof is fixed a clamp guide casting 20 with a reduced end sleeve 21 in which the inner end of the outer brace member 19 has a snug fit that will permit of a longitudinal as well as a turning movement of said member in said sleeve. Preferably this casting is removably secured to the outer end of the inner brace member by bolts 22-22 as best shown in Figs. 3 and 5 respectively and in the top and bottom sides of said casting are rectangular openings 23 and 24 respectively which register with similar openings in the pipe 18. On that end of the pipe 19 which telescopes within the pipe 18 is fixed a collar 25 having a snug sliding fit with the interior surface of the pipe 18, to coat with the sleeve 21 and thus provide the proper bearing between the pipes 18 and 19.

Disposed within the pipe 18 so as to partially surround the pipe 19, are top and bottom clamping blocks or shoes 26 and 27 respectively, each of which has a central portion 26^a-27^a respectively which extend through the openings 23 and 24 respectively, before mentioned. The central portion 27^a of the bottom block or shoe 27 is formed to provide a downwardly facing boss 28 that engages in a seat 29 on a transversely disposed pressure bar or beam 30. In the boss 28 is a vertically disposed opening 31 which registers with a similar opening 32 in the pressure beam 30. The opening 31 is of a peculiar formation in that its bottom end is made as a transversely extending slot 31^a while the top end is enlarged to provide a shoulder 31^b and in said shoulder at opposite sides of the slot are recesses 31^c-31^c. A T-shaped bolt 33 connects the said block and pressure beam together and the top end of said bolt has a head 33^a which is transversely elongated so that it may be inserted up through the slot 31^a and then turned to engage in the recesses 31^c, there being a nut 34 on the bottom end of the bolt for the purpose readily apparent. When necessary as when the braking or gripping surface of the block becomes worn, the same may be taken up or compensated therefor by placing one or more shims 35 between the boss 28 and seat 29.

In the central portion 26^a of the block or shoe 26 is a recess 26^b which receives the stem 36 of an upright pressure post 37, a pin 38 securing the stem in place in said recess. The top end of said post has a transversely extending opening 39 in which is journaled a stub shaft 40 and to the end extension of said shaft are secured depending links 41-41.

The pressure beam 30 has end trunnions 30^a-30^a and journaled thereon are the bottom ends of substantially upright links 130

42—42, the mid portions of which have guided bearing between longitudinally spaced lugs or shoulders 43—43 on each side of the bracket casting 20 as best shown in Figs. 2 5 and 3.

Associated with said links is a pair of levers 44—44. Each lever is provided at its bottom end with laterally extending, oppositely and eccentrically disposed inner and 10 outer trunnions 45 and 46 respectively. As best shown in Fig. 4, the said trunnions are offset along a plane at less than a right angle to the longitudinal plane of the lever itself. The outer trunnion of each lever bears in a 15 suitable opening in the top end of an associated link 42 while the inner trunnion of each lever bears in an opening in the bottom end of an associated link 41 as best shown in Fig. 3. The top ends of the levers 44—44 20 are connected by a cross shaft 47 and on said shaft between said levers is journaled a T-shaped cross head 48.

Secured to the pipe 18 a suitable distance inwardly from the casting 20, is a clamp like 25 bracket 49 which includes a pair of upwardly extending arms 49^a—49^a. Associated with this bracket is a cylinder 50 having front and rear end heads 51—52 respectively and in this instance the rear end head is pivoted by a 30 pin 53 to and between the bracket arm 49^a—49^a. A piston rod 54 slides through the front end head 51 and one end thereof carries a piston 55 disposed in the cylinder while the other end of said rod is connected to the 35 cross head 48 before mentioned. Suitable pressure fluid inlet and outlet 56 and 57 respectively are fixed in said heads so that motive fluid under pressure may be admitted to either end of the cylinder to move the piston 40 in the desired direction. The said inlet and outlet lead from a suitable source of supply located upon the car where usual valve mechanism (not shown) for controlling said inlet and outlet are also located.

45 The outer or free end of the pipe 19 has a ball and socket joint connection with the rear side of the wing as indicated as a whole at 58 in Fig. 1 while the inner end of the pipe 18 has a universal joint connection with the under framing of the car as indicated as a 50 whole at 59 in said figure. The ball and socket joint connection 58 is such as will permit a turning movement of the pipe 19 with respect to the wing without a separation 55 therebetween while the universal joint connection is such as will permit the brace as a whole to swing in toward or out away from the car as well as upwardly or downwardly movement. Said universal joint, however, 60 will not permit a turning or twisting of said pipe with reference to said car under framing.

The operation of the mechanism above described is as follows:—

Assume that both wings are folded in toward the car as shown at the top of Fig. 1.

When it is desired to swing one of the wings into an operative position as shown at the bottom of Fig. 1, air is admitted to the proper cylinder 14 which through the associated arm 12 will swing said wing into its operative position about the associated wing post as an axis. In this movement of the wing, the pipe section 19 will slide in the pipe section 18, it being understood that no motive fluid under pressure is in the cylinders and that the 70 levers 44 stand in the position of minimum load as indicated in dotted lines in Fig. 2 at which time the shoes or blocks 26—27 are exerting no pressure or gripping action on the pipe 19. 80

When the desired operative angular position of the wing has been reached, fluid under pressure is admitted through the conduit 56 to the rear end of the cylinder 50, fluid in advance of the piston 55 therein passing out 85 through the conduit 57 and through the valve mechanism on the car to atmosphere. As the piston moves forwardly, the levers 44 are swung into the maximum load position shown in full lines in Fig. 2. As the levers 90 thus move into said position, the eccentric trunnions on their bottom ends will produce an upward movement of the links 42 and associated parts and a downward movement of the links 41 and associated parts thus causing 95 the blocks or shoes to frictionally clamp or lock upon the pipe 19 to lock it to the pipe 18. It has been demonstrated in actual use that by clamping or frictionally gripping the blocks 26—27 upon the pipe as described, the 100 brace may be held in its extended condition under far greater load strains imposed by the wing than was heretofore possible to hold with the pin and hole type of lock previously employed. Should the wing tend to float 105 up or down due to the uneven surfaces operated upon, or if it becomes necessary to change the vertical angle of the wing, for any reason, this is possible after unlocking the pipe 19 and should the pipe 19 turn during 110 this operation, it will in no manner interfere with the relocking because no registration of locking pin and hole need be taken into consideration.

When it is desired to swing the wing back 115 into its inoperative position along side of the car, the fluid is shut off from the cylinder 50 thus releasing the gripping action on the pipe 19 and as said wing swings inwardly the pipe 19 is free to slide in the pipe 18 and thus telescope and foreshorten as is necessary.

Should the pipe engaging surface of the bottom gripping block or shoe become worn, the links 42—42 are removed, and the nut is unscrewed from the bolt 33 so that the pressure beam may be removed to permit insertion of additional and wear compensating shims between the boss 28 and seat 29 after 120 which the parts removed are replaced.

The construction described has many ad- 130

vantages. It securely holds the brace in its extended position under extreme loads and the gripping blocks or shoes grip upon any place necessary upon the pipe 19. The parts 5 employed are strong and rigid and easily accessible for inspection when necessary and cannot readily get out of order.

While in describing my invention I have referred in detail to the form and arrangement of the parts thereof, the same is to be taken as by way of illustration only and I do not wish to be limited thereto except as may be more specifically pointed out in the appended claims.

15 I claim as my invention:—

1. In a railroad spreader, a car, a side wing hinged thereto for a swinging movement toward and away from the car, a brace including telescopic members interposed between the car and side wing and which members have engaging surfaces whereby they are under certain conditions relatively turnable, a ball and socket joint connecting one of said members to the wing, a universal joint connecting the other member to the car and power actuated means operable from the car and including relatively movable clamping jaws for frictionally locking said telescopic members in the desired extended and relatively turned positions.

2. In a railroad spreader, a car, a side wing hinged thereto for a swinging movement toward and away from the car, a brace including telescopic members interposed between the car and side wing, a ball and socket joint connecting one of said members to the wing, a universal joint connecting the other member to the car, means carried by one of said telescopic members for frictional engagement with the other to lock them together and a power device also carried by said one of said telescopic members for actuating said means.

3. In a railroad spreader, a car, a side wing hinged thereto for a swinging movement toward and away from the car, a telescopic brace between the car and wing and including a member having a universal joint connection at one end with the car, and a second member having a ball and socket connection at one end with said wing and movable at its other end into and out of the other end of the first mentioned member, and power actuated frictional gripping means operable from the car and including relatively movable clamping jaws carried by said other end of said first mentioned member for locking both members together.

40 In testimony whereof, I have hereunto set my hand, this 5th day of December, 1929.

HARRY W. PROTZELLER.
